UNITED STATES PATENT OFFICE

101,421

DESIGN FOR A SYPHON

Lawrence T. Ward, New York, N. Y., assignor to
Sparklets Limited, Upper Edmonton, London,
England, a corporation of Great Britain

Application August 1, 1936, Serial No. 64,193

Term of patent 14 years

To all whom it may concern:

Be it known that I, Lawrence T. Ward, a citizen of the United States, residing at 150 East 50th Street, New York, New York, have invented a new, original, and ornamental Design for Syphons, of which the following is a specification, reference being had to the accompanying drawing, forming part thereof:

Fig. 1 is a perspective view of the syphon showing my new design;

Fig. 2 is a front view thereof on a reduced scale.

I claim:

The ornamental design for a syphon as shown,

LAWRENCE T. WARD.
